CIRCUIT INTERRUPTER

Benjamin P. Baker, Turtle Creek, and Donald C. Harker, Wilkinsburg, Pa., assignors to Westinghouse Electric Corporation, East Pittsburgh, Pa., a corporation of Pennsylvania

Application February 28, 1945, Serial No. 580,136

14 Claims. (Cl. 200—53)

1

This invention relates to circuit interrupters, in general, and, more particularly, to operating mechanisms therefor.

A general object of our invention is to provide an improved operating mechanism for a circuit interrupter which will permit high velocity motion during the initial part of the opening operation yet will permit an absorption of the kinetic energy associated with the high velocity moving parts to minimize the impact forces on the operating mechanism during the stopping of the moving parts.

A more specific object is to provide an improved circuit interrupter of the type employing a gas blast for extinction of the arc and to provide a movable inertia element which is connected by means of a lost motion coupling or connection with the movable contact structure of the interrupter.

Another object is to provide a movable inertia element connected by a lost motion coupling or connection with the movable contact to counteract the effect of the high magnetic forces encountered during the interruption of relatively high currents, of the order of 40,000 amperes or higher.

In a high speed compressed air circuit breaker, it is necessary to obtain a blast valve opening and a finite contact separation just as soon as possible. This must be obtained by large accelerating forces and high velocities. If these high velocities are allowed to continue after optimum interrupting conditions are obtained, unnecessary and damaging arc length and arc energy will result. Also, the blast valve which is mechanically tied to the contact mechanism will be closed before a current zero may occur. This hazard is worse at 25 cycle frequency than at 60 cycle frequency in that the wait for a current zero may be greater than $\frac{1}{50}$ of a second.

Our invention employs the use of a mass or an inertia element which is so proportioned and attached to the contact mechanism through a lost motion coupling or connection, that the initial part of the contact and the opening of the blast valve is obtained at high speed and independently of this mass or inertia element. As soon as optimum interrupting conditions are obtained, the mass or inertia element is engaged which causes a complete hesitation of approximately $\frac{1}{50}$ of a second in the motion of the contact after which the contact and the mass move together at considerably reduced velocity.

By the above arrangement this not only holds the blast valve open and the contact at the best separation until interruption occurs, but it de-

2

creases the velocity and shock on the mechanism which finally arrests the contact motion at the end of its stroke.

In U. S. Patent No. 1,988,610 which issued January 22, 1935 to Stanley T. Schofield and Samuel H. Boden and which is assigned to the assignee of the instant application, there is shown and claimed a novel circuit interrupting arrangement of the air break type in which the movable contact engages through a spring connection with a movable inertia element to decelerate the moving parts of the interrupter. It is a further object of our invention to improve the mechanism set forth in this patent and to provide an improved construction more adaptable to circuit interrupters of the gas blast type.

Another object of our invention is to provide an improved toggle operating arrangement in which a pair of cooperating compression springs are employed to provide improved spring characteristics to effect the breaking of the toggle during the opening operation. By such an arrangement, the impact forces resulting during the breaking of the toggle are considerably decreased, and consequently the shock on the mechanism is greatly reduced.

Another object is to provide an improved shock absorbing mechanism for the movable parts of a circuit interrupter in which a portion of a mass or inertia element is connected by way of a lost motion coupling or connection to the movable contact and also in which another portion of the mass or inertia element is resiliently mounted with respect to the afore-mentioned portion. Such a relative resilient mounting arrangement between the two portions of the mass or inertia element is especially desirable during the closing operation.

Further objects and advantages will readily become apparent upon a reading of the following specification taken in conjunction with the drawings, in which:

Figure 1 is a side elevational view of a gas blast type of circuit interrupter embodying our invention and shown in the closed circuit position;

Fig. 2 is a fragmentary enlarged side elevational view, partly in section of the improved operating mechanism of the interrupter, the parts being shown in the closed circuit position;

Fig. 3 is a fragmentary plan view of a portion of the operating linkage taken substantially along the line III—III of Fig. 2;

Fig. 4 is a fragmentary plan view of a portion of the operation linkage;

Fig. 5 illustrates graphically the improved re-

sults of our invention as compared to the result encountered when no shock absorbing mechanism is provided; and

Fig. 6 graphically illustrates the spring characteristics of the compression springs employed in our improved toggle "kick-off" arrangement.

Referring to the drawings and more particularly to Fig. 1 thereof, the reference numeral 1 designates a tank filled with a suitable arc extinguishing gas under pressure, in this instance compressed air. The tank supports at its upper end an outlet conduit 2 which branches at its upper end into further conduits 3, 4. The conduit 3 leads through a valve casing 5 to a blast tube 6, the passage of gas through the valve casing 5 being controlled by a blast valve operating mechanism generally designated by the reference numeral 7.

The upper end of the blast tube 6 terminates adjacent to the contact gap which is formed during the opening operation by separation of the movable contact 8, of C-shaped configuration, from the stationary contact structure 9. A line terminal 10 is electrically connected to the stationary contact structure 9, and a second line terminal 11 is electrically connected to the movable contact 8.

Consequently, in the closed circuit position of the interrupter, as shown in Figs. 1 and 2, the electrical circuit therethrough comprises the line terminal 10, stationary contact structure 9, movable contact 8 to the other line terminal 11 of the interrupter. To effect an opening operation of the interrupter, suitable operating mechanism, hereinafter more fully described, is actuated to cause downward movement of an insulating operating rod 12 which is pivotally connected at 13 to the movable contact 8. The lower end of the insulating operating rod 12 is secured by means of a threaded engagement to a metallic U-shaped member 14, the lower end of which is bifurcated as at 15 to form two opposing legs 16, 17 more clearly shown in Fig. 4 and pivotally mounted on a pin 18. The pin 18 passes through a bifurcated portion 19 of a high speed operating lever 20, the latter being pivotally mounted on a pin 21 to a pair of hand operating levers 22 rigidly secured together by a bolt 23 to move as a unit.

The hand operating levers 22 are pivotally mounted on pins 24 (see Fig. 4) to a pair of support plates 25, the latter having a configuration more clearly shown in Fig. 1 and spaced apart a distance more clearly shown in Fig. 4.

Referring to Fig. 2, it will be observed that the pin 21 also pivotally supports a pair of toggle links 26 having a knee pin at 27, the latter passing through the other leg 28 of the toggle which is generally designated by the reference numeral 29. Fig. 2 shows the toggle 29 in its overcenter position in the closed circuit position of the interrupter, an adjustable stop 30 being provided to limit the overcenter travel of the toggle 29.

The lower leg 28 of the toggle 29 is preferably formed as an integral part of a bell crank 31 pivotally mounted at 32 to a stationary pivot and having a lower portion 33 making pivotal connection at 34 to a pair of short links 35. As viewed in Fig. 2, the left-hand ends of the short links 35 make pivotal connection at 36 to a cross-head 37, the latter being movable by a piston rod 38. At the left-hand end of the piston rod 38 is a piston 39 which reciprocally travels in an operating cylinder 40.

A suitably shaped casting member 41 is secured to the right-hand end 42 of the operating cylinder 40 and has formed therein a pair of

guide slots 43 which serve to guide the reciprocating motion of the cross-head 37. Preferably, an upstanding portion 44 of the bifurcated casting member 41 forms a bearing for the stationary pivot pin 32.

The closing motion of the piston 39 is controlled by a magnetic closing valve 45 which permits the admission of compressed air to the piston contained in a main closing valve 46, the latter controlling the admission of fluid from a reservoir 47 leading from the tank 1 to the left-hand end of the operating cylinder 40.

It will be observed, referring to Fig. 2, that the conduit 3 leads into the valve casing 5, the passage of compressed air therethrough being controlled by a blast valve 48 having a stem 49. The valve stem 49 makes a pivotal connection at 50 to an actuating member 51 pivotally mounted at 52 to the wall 53 of the valve casing 5, a compression spring 54 serving to bias the actuating arm 51 in a clockwise direction about its pivotal mounting 52 to effect closing of the blast valve 48.

The particular blast valve operating mechanism shown forms no part of our invention and may be of any suitable type. Preferably, it is of the adjustable roller type similar to that illustrated and claimed in U. S. Patent No. 2,310,779 which issued February 9, 1943 to Erik H. Hall and Raymond H. Leitzel and which is assigned to the assignee of the instant application. However, since our invention is not concerned with the blast valve mechanism it has been simplified for purposes of illustration and comprises a pair of opposed externally extending arms 55 between which is disposed a roller 56 mounted on a pin 57.

The roller 57, in the closed circuit position of the interrupter, as shown in Fig. 2, comes closely adjacent to a cam surface 58 of the high speed operating lever 20, the latter having a bifurcated portion 59 (see Fig. 4) between the legs of which is positioned a roller 60. The roller 60 of the high speed operating lever 20 is latched in position by a latch mechanism generally designated by the reference numeral 61.

The latch mechanism 61 comprises an opposed pair of latch levers 62 pivotally mounted on a stationary pivot at 63 and making pivotal connection at 64 to a spring guide rod 65, the latter passing through a fixed support plate 66. Two compression springs 67, 68 are mounted on the spring guide rod 65 and serve to bias the latch levers 62 in a counter-clockwise direction about the fixed pivot pin 63.

Extending between the latch levers 62 is a trigger lever 69 pivotally mounted on a stationary pivot at 70 and biased in a clockwise direction thereabout by a compression spring 71. The right-hand end of the trigger lever 69 forms a latch 72 which in the closed circuit position of the interrupter, as shown in Fig. 2, abuts against a latch member 73. The latch lever 73 is pivotally mounted about the pin 63 and is biased in a clockwise direction thereabout by a compression spring 74. The latch levers 62 have extending portions 75 between which are fixedly secured a guide member 76. The latch member 73 has a latching portion 77 which serves to latch in position the roller 60. A solenoid 78 is employed to effect tripping motion of the trigger lever 69 during the opening operation. When the solenoid 78 is thus energized, the trigger lever 69 rotates in a counterclockwise direction about the pivot 70 against the biasing action exerted by the compression spring 71 to permit the latch member 73 to be rotated in a counterclockwise direction about the pivot pin 63 against the biasing action exerted

by the compression spring 74. This occurs because of the biasing action exerted by the opening accelerating springs 79 transmitted through the accelerating rod 80 and link 81 through the pin 18 to bias the high speed trip lever 20 in a clockwise direction about the pivot pin 21, which remains stationary during the initial portion of the opening operation.

Thus, upon release of the latch mechanism 61, there is immediately effected clockwise rotation of the high speed trip lever 20 about the pin 21 which during this complete clockwise rotation of the operating lever 20 remains stationary. It will be noted that clockwise rotation of the high speed operating lever 20 about the pin 21 following unlatching of the roller 60 by the latch mechanism 61 causes downward movement of legs 16, 17 to effect through the operating rod 12 opening clockwise rotation of the movable contact 8 away from the stationary contact 9 around the pivot pin 82. Simultaneously, the cam portion 58 of high speed operating lever 20 strikes the roller 51 of the valve mechanism 7 to effect opening of the blast valve 48 against the biasing action exerted by the gas pressure and the compression spring 54. Thus, opening motion of the blast valve 48 is synchronized with opening motion of the movable contact 8.

The opening of the blast valve 48 permits compressed gas to pass from the conduit 3 through the valve casing 5, upwardly through the blast tube 6 to effect extinction of the arc drawn at the top of the blast tube 6 between the movable contact 8 and the stationary contact 9. Preferably a suitable interrupting structure generally designated by the reference numeral 83 and preferably comprising notched spitters is employed in conjunction with the upward blast of gas. The interrupting structure 83 forms no part of our invention but is preferably of a type set forth and claimed in U. S. Patent No. 2,272,380 which issued February 10, 1942 to Leon R. Ludwig, Herbert L. Rawlins and Benjamin P. Baker and which is assigned to the assignee of the instant application.

During the interruption of relatively high currents, such as of the order of 40,000 amperes, and especially when interrupting alternating currents of a frequency of 25 cycles per second, the magnetic forces encountered during the opening motion of the contacts are considerable because of the loop effect of the current. Thus, if no provision is made to take care of the extremely high forces involved due to this magnetic action, a travel curve is obtained as indicated by the reference numeral 84 in Fig. 5. It will be observed that the slope of the travel curve 84 is proportional to the contact velocity; consequently, if no means are provided to absorb the high kinetic energies involved, extremely high velocities of the movable parts are encountered, as indicated by the travel curve 84.

To overcome the high kinetic energies involved as a result of the high magnetic forces encountered, we provide the kinetic energy absorbing mechanism generally designated by the reference numeral 85 and comprising a mass or inertia element 86 associated with a rod 87 connected by a lost motion coupling or mechanical connection 88 to the movable contact 8. More specifically, the mass or inertia element 86 consists of several metallic discs 89 of relatively large weight threadedly secured at 90 to the left-hand end 91 of the rod 87. A nut 92 may also be provided. Loosely mounted on the rod 87 are a disc-like

resilient member 93, in this instance composed of leather, and one or more movable weight discs 94. Both the leather ring 93 and the metallic weight ring 94 are loosely mounted on the portion 95 of the rod 87, a compression spring 96 biasing the rings 93, 94 against the fixed discs 89. The right-hand end of the compression spring 96 seats against a flange 97 rigidly fixed to the rod 87. Preferably, to relieve some of the weight which must be supported by the rod 87, the left-hand disc 89 has a lug 98 fixed thereto which is pivotally connected at 99 to a pair of links 100, the upper ends of which are pivotally mounted at 101 to a fixed support 102 which is preferably a portion of the supporting framework of the interrupter. Consequently, the additional support means 103 relieves the stress imposed on the rod 87, but nevertheless permits substantial axial movement of the rod 87 with respect to the fixed support 102.

The right-hand end of the rod 87 is threadedly secured to a bifurcated member 104 more clearly shown in Fig. 3 through which passes two pins 105, 106. The pin 105 pivotally mounts a lever 107 to the bifurcated rod end 104 and hence to the rod 87. The lever 107 is preferably formed as an integral part of a cylinder 108 having a lever 109 integrally formed therewith adjacent the intermediate portion of the cylinder 108, as shown more clearly in Fig. 3. The cylindrical bearing 108 is pivotally mounted on a pin 110 which extends through the two support plates 25 being supported thereby.

The lever 109 has a pin 111 extending therethrough, the pin 111 being slidably guided in two slots 112 formed in two links 113, the upper ends of which are pivotally mounted at 114 to a downwardly projecting portion 115 of a spring-follower member 116, the latter being biased downwardly by the opening accelerating spring 79 and being movable within the spring-guide cylinder 117.

The pin 106 pivotally mounts the bifurcated link 118 to the bifurcated rod end 104. A pin 119 which extends through the two legs 120, 121 of the bifurcated link 118 pivotally mounts a link 122, the right-hand end of which is fixed to a shaft 123, the latter extending within a shock absorbing cylinder 124. The mechanism within the shock absorbing cylinder 124 is such as to inhibit rotative motion of the shaft 123 and supplements the shock absorbing action which takes place in the kinetic energy absorbing mechanism 85.

It will be observed that because of the lost motion coupling 88 the initial opening travel of the movable contact 8 is not impeded. Consequently, in the operation of our interrupter, we obtain an initial travel curve 125 of Fig. 5 which would develop into the travel curve 84, should no decelerating mechanism be provided. However, at the point P in Fig. 5, the top of the slots 112 strike the pin 111 to immediately bring into action both the shock absorbing mechanism 124 and the kinetic energy absorbing mechanism 85 to result in the modified travel curve 126 of Fig. 5.

There may occur at high currents, such as 40,000 amperes or over, a slight bounce, as indicated by the hump portion 127 of the travel curve 126. However, despite this possibility, the modified travel curve 126 of Fig. 5 considerably reduces the opening velocity of the movable parts of the interrupter after the point P is reached. Consequently, the shock is removed from the operating mechanism, and the contacts are slowed down or substantially halted sufficiently in the 75 space of time represented by "t," as shown in Fig.

5, when the blast valve is open to effect interruption at a current zero.

Thus, by employing our invention, we quickly obtain the optimum contact gap necessary for interruption, designated by the point P, and immediately when this optimum contact gap is obtained, slow down the mechanism so that there will surely be time enough for a current zero to occur. Without employing such a decelerating mechanism, difficulties were encountered inasmuch as the extremely high velocity of the contact parts during the interruption of high amperage currents on 25 cycles permitted the cam surface 58 of the operating lever 20 to ride off of the roller 57 of the blast valve mechanism 7 permitting the blast valve to close even before a current zero had been obtained. But by employing the kinetic energy absorbing mechanism 85 in conjunction with the shock absorber 124, the contact velocity is reduced to such an extent following the attainment of a sufficient contact gap of optimum dimensions that a current zero will surely occur, and consequently, interruption of the circuit at this current zero will ensue.

It is to be noted that the high speed operating lever 20 completes its clockwise rotative travel about the pivot 21 effecting interruption of the circuit and bringing the movable contact 8 to a complete halt before any motion takes place whatsoever of the main operating levers 22. Thus, upon completion of the clockwise rotative motion of the high speed operating lever 20 about the pivot 21 until the flange 128 secured to the accelerating rod 80 strikes the leather washer 129, then and then only do the operating levers move in a clockwise direction about the pivot pins 24 (see Fig. 4).

This results inasmuch as when the flange 128 strikes the resilient washer 129 the compressive forces tending to hold the toggle 29 in its over-center position, as shown in Fig. 2, are reduced to such an extent that then and then only is the relatively weak biasing means 130 associated with the toggle "kick-off" rod 131 sufficient to effect breakage of the toggle 29 to thereby rotate the bell crank 31 about its pivot 32 in a clockwise direction to effect leftward movement of the piston 39.

Thus, to retrieve the closing linkage of the main circuit breaker operating mechanism, the "kick-out" bias means 130 is used to push the linkage overtoggle and to cause the toggle lever 31 to rotate clockwise about point 32 assisted by the weight of the high speed lever 20 and the main operating levers 22.

Initially, considerable force is required to raise these weights as the linkage comes into toggle and to overcome static friction. If a single spring is used which is sufficiently strong to overcome these forces, it provides too much energy after the linkage goes overtoggle and so results in too much of an impact force on the linkage at the end of the opening stroke. Moreover, the static friction forces are widely variable depending on the condition of the various bearings and the impact with which the linkage has been closed. These static friction forces are a considerable portion to the total force required.

By using two compression springs 132, 133 in series, one a short stiff spring 132, and another a weaker longer spring 133, which goes solid near the end of the closing stroke, a high initial force is available for breaking the static friction load and raising the weight of the linkage overtoggle, while at the same time providing a more moder-

ate force for following through the linkage to the open position. Referring to Fig. 6 and remembering that the energy imparted to the linkage is the area under the curves, it is evident that the area under curve RST is considerably less than under curve RT, and hence there is considerably less impact to the linkage when it reaches the open position.

An additional advantage of the invention lies in the fact that manufacturing variations which may introduce considerable different initial loads are readily adjusted by putting a washer or washers 134 under the stiff spring. This is not the case for a single spring. (Compare "d" and "d'".)

Following the breaking of the toggle 29, the high speed operating lever 20 is rotated in a counterclockwise direction about the pivot pin 18, which during this time is stationary, flange 128 having struck and thereby having been stopped by the leather washer 129. This counterclockwise travel of the high speed lever 20 continues until the roller 60 attached thereto (Fig. 4) strikes the tongue 76, thereby moving the latch levers 62 in a clockwise direction about the pivot pin 63 permitting the compression spring 74 to force the latch lever 62 over the roller 60 and thus permitting the trigger lever 69 to be rotated in a clockwise direction about the pin 70 by the compression spring 71. Thus, the high speed trip lever 20 is relatched by the latch mechanism 61 at the end of the opening stroke of the interrupter.

To close the interrupter, the magnetic closing valve 45 is operated by means not shown to thereby permit operation of the closing valve 46 to permit compressed gas to pass from the reservoir 47 to the left-hand end of the operating cylinder 40 to force the piston 39 toward the right. This effects rightward movement of the piston rod 38 and correspondingly rightward movement of the cross-head 37 to effect extension of the toggle 29 and consequently counterclockwise rotation of both the high-speed lever 20 and the operating arms 22 about their concentric axes of rotation, pins 24 and roller 60. This effects upward movement of the operating rod end 15 to effect contact closure while simultaneously effecting compression of the accelerating compression springs 79.

Also, this closing motion forces the rod 81 to the left, thereby moving only the discs 89, the compression spring 96 being relied upon to effect closing motion of the disc 93, 94 thereafter. Consequently, the closing operation is not effected by the weight of the disc 94 which is freely slideable upon the rod 81. During the opening operation, the disc 94 is picked up by the discs 89 through the energy absorption member 93.

The invention has a distinct advantage when closing against a high current, for the magnetic forces involved by spark-over near the end of the closing stroke tend to slow down the closing movement of the movable contact 8. However, the inertia mass 86 continues to move to the left causing the pin 111 to strike the upper end of the slots 112 during such a final portion of the closing stroke to give a final impact force to the movable contact 8 near the end of the closing stroke to force it into engagement with the stationary contact 9.

Thus, the mass 86 is so proportioned that in comparison with the magnetic forces and masses of the moving parts of the breaker that a hesitation of the contact motion is produced sufficiently long to allow for circuit interruption with

the contact separation at its optimum value for arc extinction. This hesitation also makes it possible to obtain extremely high accelerations and high velocities to obtain this optimum contact separation and then slow down the mechanism to the point where the energies which have to be absorbed in the full open position of the breaker do not damage the mechanism.

It is desirable to arrest the high speed motion of the contact 8 when the conditions are right for arc extinction so that the blast valve 48 will not be permitted to reclose before a current zero is reached and arc extinction can be obtained. The difference between no-load and full load acceleration produced by the magnetic forces is very great.

The advantages obtained by the use of the mass or inertia element 86 are:

1. To hold the contacts separated at their optimum value for arc extinction until a current zero is reached, regardless of the magnitude of the current and magnetic forces;

2. To permit high accelerations and high velocities through the early part of the opening stroke and then to decrease this velocity by increasing the mass of the moving system, so that the entire system will approach its final open position with a greatly reduced velocity and consequently a correspondingly reduced energy;

3. To obtain hesitation in the mechanism which controls the blast valve operation, so that flow of air for arc extinction is insured at the time of zero current.

4. To provide an impact force on the movable contact near the end of the closing stroke to overcome the magnetic forces involved by spark-over at this time, when closing against extremely high currents. This results since the magnetic forces will tend to impede the final closing motion of the movable contact, and at this time the inertia mass will take up the play in the lost motion connection to strike the movable contact, thereby forcing it into engagement with the stationary contact structure despite the effect of the magnetic forces which impede the closing operation.

5. To provide the effect of a large mass as a part of the moving contact system for closing operation, but not for the early portion of the opening operation so that the high pressures in the closing cylinder may be used in the closing operation without producing excessive and damaging velocities to the additional inertia attached to the moving system during the closing operation. This reduces the contact speed to a desirable value and at the same time permits high pressures in the closing cylinder so that when magnetic forces are encountered, as a result of spark-over in the interrupter, very large forces are available in the closing mechanism to instantly overcome these magnetic reactions.

From the foregoing description, it is apparent that the mass 86 is so arranged that a part of it is rigidly secured to the rod 87 while part of it is slidably mounted on the rod 87 with a resilient member 93 between the slidably mounted portion and the fixed portion so that when the rigidly attached mass is engaged the slidably mounted mass is then engaged through the resilient member; this consequently decreases the shock on the mechanism. Likewise, increasing the speed of the closing of the breaker is not affected by the portion of the mass 86 which is slidably mounted on the rod 87, the latter portion of the mass being forced to follow the rigidly

attached portion 89 by the action of the compression spring 96. The force of the compression spring 96 is adjusted so that if the breaker is required to make an opening operation immediately following a closing operation, the slidably mounted mass will have reached the end of its stroke sometime later than the rigidly attached mass, but before the motion of the contacts has reversed.

10. Certain features of the operating mechanism relating to the high speed rotation of the high speed operating lever 20 together with the synchronized opening of the blast valve 48 thereby are described and claimed in a concurrently filed application by Howard M. Wilcox and Raymond H. Leitzel, Serial No. 580,138 now Patent No. 2,428,482, issued Oct. 7, 1947, and assigned to the assignee of the instant application.

From the foregoing description, it will be apparent that we have provided a mass or inertia element which is engaged through a lost motion coupling or connection during the opening operation, but which is not engaged by a lost motion coupling during the closing operation. It will also be apparent that we have provided an improved toggle breaking arrangement which minimizes the impact forces produced. Further, it is to be observed that we have counteracted the effect of high magnetic forces involved during the interruption of high ampereage currents.

Although we have shown and described a specific structure, it is to be clearly understood that the same was merely for the purpose of illustration and that changes and modifications may readily be made therein by those skilled in the art without departing from the spirit and scope of the appended claims.

We claim as our invention:

1. In a circuit interrupter, a movable contact, means for moving the movable contact to open and closed positions at high speed, a rod, an inertia mass having one portion secured to the rod and having another portion loosely mounted on the rod so as to be movable relative thereto, a compression spring mounted on the rod and having one end seated rigidly with respect to the rod and having the other end biasing the loosely mounted portion against the first-mentioned portion, and a lost-motion mechanical connection between the movable contact and the rod arranged to impart movement to said rod and inertia mass following a predetermined contact movement in the opening direction, said spring enabling movement of said loosely mounted portion with respect to said secured portion to reduce the inertia effect of said mass during the initial closing movement of said contact.

2. In a circuit interrupter, a movable contact, means for moving the movable contact to open and closed positions at high speed, a rod, an inertia mass having one portion secured to the rod and having another portion loosely mounted on the rod so as to be movable relative thereto, a compression spring mounted on the rod and having one end seated rigidly with respect to the rod and having the other end biasing the loosely mounted portion against the first-mentioned portion, a lost-motion mechanical connection between the movable contact and the rod arranged to impart movement to said rod and inertia mass following a predetermined contact movement in the opening direction, said spring enabling movement of said loosely mounted portion with respect to said secured portion to reduce the inertia effect of said mass during the initial closing movement

11

of said contact, and a resilient member interposed between the two portions.

3. In a circuit interrupter, a movable contact, means for moving the movable contact to open and closed positions at high speed, a rod, an inertia mass having one portion secured to the rod and having another portion loosely mounted on the rod so as to be movable relative thereto, a compression spring mounted on the rod and having one end thereof seated rigidly with respect to the rod and having the other end biasing the loosely mounted portion against the first-mentioned portion, a lost-motion mechanical connection between the movable contact and the rod to actuate said inertia mass to thereby reduce the contact opening speed following a predetermined movement in the opening direction and to assist said contact moving means in moving said contact to closed position, and a shock absorber operatively associated with said rod and actuated at the same time the rod is actuated by the movable contact.

4. In a circuit interrupter, a movable contact, means for moving the movable contact to open and closed positions at high speed, a rod, an inertia mass having one portion secured to the rod and having another portion loosely mounted on the rod so as to be movable relative thereto, a compression spring mounted on the rod and having one end seated rigidly with respect to the rod and having the other end biasing the loosely mounted portion against the first-mentioned portion, a lost-motion mechanical connection between the movable contact and the rod whereby said inertia mass reduces the contact opening speed following a predetermined movement in the opening direction and assists said contact moving means in moving said contact to closed position, a resilient member interposed between the two portions, and a shock absorber coupled to said rod and actuated at the same time the rod is actuated by the movable contact.

5. In a circuit interrupter, a movable contact, operating means for providing high speed motion of the movable contact, inertia means connected by a lost motion mechanical connection to the movable contact, said inertia means comprising a first portion, resilient means disposed between a second portion of the inertia mass and the first-mentioned portion thereof so that during a part of the opening operation the two portions move together, and during the closing operation the movement of the second-mentioned portion is delayed with respect to the first-mentioned portion.

6. In a circuit interrupter, a relatively light moving contact system, a relatively heavy inertia system, operating means including a toggle for operating said contact system, piston means for actuating said toggle to effect closing motion of both the relatively light moving contact system and the relatively heavy inertia system, a lost motion connection mechanically connecting the relatively light moving contact system and the relatively heavy inertia system, the relatively heavy inertia system comprising a first portion and a second portion, and resilient means between the two portions.

7. In a circuit interrupter of the gas blast type, a relatively light moving contact system, a relatively heavy inertia system, a lost motion connection mechanically connecting the aforementioned two systems, operating means including a toggle for effecting closing motion of both the aforementioned two systems, piston means for

12

actuating said toggle to effect closing motion of the operating means, the arrangement having the lost motion connection effective during the opening operation to delay actuation of said inertia system and effective during the closing operation when closing against heavy currents to cause said inertia system to assist said operating means in the closing operation.

8. In a circuit interrupter, movable contact means, operating mechanism for effecting high speed opening and closing movement of said movable contact means, an inertia mass, a movable member to which at least a portion of said inertia mass is rigidly secured, a lost motion coupling connecting said movable member to said movable contact means to cause said inertia mass to decelerate the movement of said movable contact means during opening movement after said movable contact means has moved a predetermined distance, said lost motion coupling causing said inertia mass to decelerate movement of said movable contact means during closing movement after said movable contact means has moved a predetermined distance, and said lost motion coupling thereafter during said closing movement transmitting kinetic energy from said inertia mass to said movable contact means to assist said operating mechanism in moving said movable contact means to the closed position.

9. In a circuit interrupter comprising movable contact means, means for effecting high-speed opening and closing movements of said movable contact means, a longitudinally movable member, a first inertia mass rigidly secured to one end of said member, a second inertia mass mounted on said longitudinally movable member adjacent said first inertia mass, a lost-motion coupling connecting the other end of said longitudinally movable member and said movable contact means in a manner to cause said contact means to pick up said inertia masses after a predetermined travel in opening direction to thereby decelerate the opening movement of said contact means and to cause said contact means to pick up said first inertia mass after a predetermined travel in closing direction to decelerate the closing movement of said contact means, and said longitudinally movable member being movable relative to said second inertia mass mounted thereon during the closing movement of said contact means to thereby provide less deceleration of said contact means during closing movement than during opening movement of said contact means.

10. In a circuit interrupter comprising movable contact means, means for effecting high-speed opening and closing movements of said contact means, a movable member, a first inertia mass rigidly secured to said movable member, a second inertia mass loosely mounted on said movable member adjacent said first inertia mass, a lost-motion coupling connecting said movable member to said movable contact means in a manner to cause said movable contact means to pick up both of said inertia masses after a predetermined travel in opening direction to decelerate opening movement of said movable contact means and to cause said movable contact means to pick up said first inertia mass after a predetermined travel in closing direction to decelerate the closing movement of said movable contact means, and resilient means between said movable member and said second inertia mass to permit movement of said movable member relative to said second inertia mass during closing movement of said movable contact means to thereby provide less decel-

13

eration of said movable contact means during closing movement than during opening movement of said movable contact means.

11. In a circuit interrupter comprising movable contact means, means for effecting high-speed opening and closing movement of said movable contact means, decelerating means for decelerating both opening and closing movements of said movable contact means comprising a movable member, an inertia mass comprising a first portion rigidly fixed to said movable member and a second portion loosely mounted on said movable member, a lost motion coupling comprising a pin and slot connection coupling said movable member to said movable contact means to cause said inertia mass to decelerate opening movement of said movable contact means at a predetermined time during said opening movement and to cause said first portion of said inertia mass to decelerate the closing movement of said movable contact means at a predetermined time during said closing movement, and said movable member being movable relative to said second portion of said inertia mass during the closing movement of said movable contact means to decrease the decelerating effect of said inertia mass during closing movement of said movable contact means.

12. In a circuit interrupter, movable contact means, operating means for effecting high-speed opening and closing movement of said movable contact means, decelerating means for decelerating both the opening and closing movements of said movable contact means comprising a movable member, an inertia mass including a first mass fixedly secured to said movable member and a second mass loosely mounted on said movable member adjacent said first mass, a lost motion coupling connecting said movable member to said movable contact means to cause said decelerating means to decelerate the opening and closing movements of said movable contact means at a predetermined time during each movement, said movable member being movable relative to said second mass during the closing movement to decrease the decelerating effect of said decelerating means during the closing movement of said movable contact means, spring means for returning said second inertia mass to its initial position, and both of said inertia masses being effective during the closing movement when closing against heavy currents to assist said operating means in closing said movable contact means.

13. In a circuit interrupter, movable contact means for drawing an arc, a blast valve for directing an arc extinguishing blast of gas to extinguish

14

said arc, operating means for effecting high speed opening and closing movement of said movable contact means and said blast valve, means comprising an inertia member for decelerating the opening and closing movements of said movable contact means, a lost motion coupling connecting said inertia member to said movable contact means to cause said inertia member to decelerate the opening movement of said movable contact means only after said blast valve has opened and said movable contact has opened to a predetermined point most favorable for arc extinction, and said lost motion coupling causing said inertia member to first decelerate the closing movement of said movable contact means and then assist said operating means to move said movable contact means to the closed position.

14. In a circuit interrupter, stationary and movable contact means for drawing an arc, a blast valve for directing an arc extinguishing blast of gas to extinguish said arc, means for effecting high-speed opening and closing movement of said movable contact and opening of said blast valve, decelerating means comprising an inertia member for decelerating both the opening and closing movements of said movable contact means, a lost motion coupling connecting said inertia member to said movable contact means to cause said decelerating means to decelerate the opening movement of said movable contact only after said blast valve has opened and said movable contact has opened a predetermined distance to a point most favorable for arc extinction, and said lost motion coupling causing said inertia member to decelerate the closing movement of said movable contact.
